(57) **CLAIM**

The ornamental design for a polisher, as shown and described.

DESCRIPTION

FIG. 1 is a top perspective view of a polisher showing our new design.

FIG. 2 is a left side elevational view thereof.

FIG. 3 is a top plan view thereof.

FIG. 4 is a right side elevational view thereof.

FIG. 5 is a bottom plan view thereof.

FIG. 6 is a front elevational view thereof.

FIG. 7 is a rear elevational view thereof.

FIG. 8 is a top perspective view of a second embodiment thereof.

FIG. 9 is a left side elevational view thereof.

FIG. 10 is a top plan view thereof.

FIG. 11 is a right side elevational view thereof.

FIG. 12 is a bottom plan view thereof.

FIG. 13 is a front elevational view thereof; and,

FIG. 14 is a rear elevational view thereof.

The FIGS. 8-14 drawings are partially lined for the color black, however, the black color extends across the entire portion of the polisher shown in solid line.

The broken lines represent portions of the polisher that form no part of the claim.

1 Claim, 12 Drawing Sheets
